United States Patent Office.

ADDISON CROSBY, OF WESTFIELD, NEW YORK.

Letters Patent No. 91,610, dated June 22, 1869.

IMPROVEMENT IN PADLOCKS.

The Schedule referred to in these Letters Patent and making part of the same.

To all whom it may concern:

Be it known that I, ADDISON CROSBY, of Westfield, in the county of Chautauqua, and State of New York, have invented a new and useful Improvement in Locks; and I do hereby declare that the following is a full, clear, and exact description thereof, which will enable others skilled in the art to make and use the same, reference being had to the accompanying drawings, forming part of this specification, in which—

Figure 1 is a vertical section of my invention, taken in the line *x x*, fig. 3.

Figure 2 is a vertical section of the same, taken in the line *y y*, fig. 3.

Figure 3 is a horizontal section of the same, taken in the line *z z*, fig. 1.

Figure 4 is a detached perspective view of the key. Similar letters of reference indicate like parts.

This invention is designed as an improvement upon the ordinary padlock, whereby simplicity is obtained, with security, or difficulty in picking or illegitimately opening the lock, while the interior of the same is protected from moisture, and prevented from being choked or clogged up with sleet or ice during the winter-season.

In the accompanying sheet of drawings—

A represents the case of the lock, and

B is the bow, or shackle, which works up and down, said bow or shackle having a straight portion, *a*, which works within the case, as shown in figs. 1 and 2, a spiral spring, *b*, within the case, throwing the shackle upward whenever it is released from dogs, which retain or hold it down in a locked position or state.

C C are the dogs which are fitted loosely on an arbor, *D*, within the case.

Said dogs have springs *c* attached, which springs have a tendency to keep the lower ends of the dogs in a notch in the straight portion of the bow or shackle, in order to hold the same in a locked state. (See more particularly fig. 2.)

E represents the tumblers, four being shown in the drawings, two at each side of the dogs.

These tumblers are suspended by pivots *a* $\times$, and have oblong curved slots *d* made in them, through which the arbor *D* passes.

The lower edges of the tumblers are notched, or serrated, and each has an upright slot, *e*, made in it, said slot being at different points in the several tumblers.

The dogs *C C* have each an arm, *F*, pivoted to them, and these arms extend down at the outer sides of the tumblers, and have each a small bar, *d* $\times$, projecting from them at right angles, said bars extending underneath the tumblers.

The lower parts of the arms *F* work between guide-pins *e* $\times$ *e* $\times$, which keep them in place. (See fig. 2.)

From the above description it will be seen, that in order to unlock the lock, the lower ends of the dogs *C C* must be thrown out of the notch in the upright straight part *a* of the bolt or shackle, and, in doing this, the arms *F* will necessarily be raised, and consequently the tumblers *E* must first be adjusted to bring the slots *e* in line with each other, and the bars *d* $\times$ of the arms *F*, in order that said arms may rise.

This result can only be obtained through the medium of a proper key, *G*, as shown in fig. 4, said key having two lateral bits *g g* projecting out at a greater or less distance, corresponding to the position of the slots *e* in the lower edges of the tumblers *E*.

The prongs of the key are inserted up through openings in the bottom of the lock-case, and the bits *g g* first adjust the tumblers *E E*, so as to bring the slots *e* in the several tumblers in line with each other, and the ends of the prongs *f f* then come in contact with the upper ends of the dogs *C C*, and throw the lower ends of the latter out from the notch in the straight part *a* of the bow or shackle *B*, and the spring *b* then throws the latter upward.

The tumblers are provided with springs *h*, to give them their return movement, as the prongs of the key are withdrawn.

It will be perceived that the lower edges of the tumblers *E* have a wide movement, or sweep, compared with the movement or sweep at the points *b* $\times$, where the bits *g* of the key act against them, and hence it will be seen that it would be a very difficult matter, if not utterly impossible, to adjust the slots *e* of the tumblers in line with each other by any illegitimate means, for the slightest movement of the tumbler at *b* $\times$, will cause the lower edges, where the slots *e* are made, to move a considerable distance.

It will further be seen that the lower parts of the tumblers are in such a position that they cannot be reached and acted upon by picks, and tampered with.

I claim as new, and desire to secure by Letters Patent—

1. The rising and falling bow or shackle *B*, in connection with the dogs *C C*, the tumblers *E*, provided with the slots *e*, and the arms *F*, having the bars *d* $\times$ attached, all arranged to operate in the manner substantially as and for the purpose set forth.

2. The key *G*, provided with two prongs *f f*, having lateral bits *g g*, when used in connection with the tumblers *E* and dogs *C*, all arranged to operate substantially as and for the purpose set forth.
